UNITED STATES PATENT OFFICE

2,509,988

RAILWAY CAR COUPLER SUPPORT

Karl T. Nystrom, Chicago, Ill., assignor to Standard Railway Equipment Manufacturing Company, Chicago, Ill., a corporation of Delaware

Application November 29, 1946, Serial No. 713,178

6 Claims. (Cl. 213—61)

1

The object of the invention is to provide means in a railway car coupler support and centering device to resiliently support the coupler independently of the centering mechanism but cooperative therewith so as to resiliently support the coupler in all positions of the centering mechanism; that is, whether the coupler is in normal central position or moved laterally therefrom.

A further object is to provide means in such a device to support the coupler or its carrier independently of the resilient means upon abnormal downward pressure of the coupler.

A still further object is to provide means in such a device to regulate or adjust the height of the coupler carrier (and the coupler) from the rail of the track.

In the drawings:

Figure 1 is a partial front elevation and partial vertical central sectional view of a railway car striking casting with my device applied thereto, showing the parts as they would occur when the coupler is in normal central position.

Figure 2 is a side elevation of Figure 1.

Figure 3 is a section on line 3—3 of Figure 1.

The left half of Figure 4 is a section on line 4—4 of Figure 1.

The right half of Figure 4 is a section on line 5—5 of Figure 1.

Figure 5 shows the carriage by itself.

Figure 6 is an end elevation of Figure 5.

In the drawings the striking casting 2 is fixed to a railway car in any desirable manner and the tie bar 3 is secured to the striking casting by the rivets 4. The tie bar 3 may be cast integral with the striking casting 2 if preferred.

The coupler 5 moves longitudinally, laterally and vertically in service.

The carrier 7 is provided with lugs 8 or other means to cause it to move laterally with the coupler 5.

The carriage 10 and some member fixed to the car (such as the tie bar 3) are provided with spaced pairs of opposed curved surfaces 11—12 and a roller 13 is interposed between each pair of surfaces, and cooperative therewith to return the carriage 10, carrier 7 and coupler 5 to normal central position when free to do so.

The carrier 7 fits between the walls 14 of the carriage 10 so as to move laterally therewith. The carrier 7 is normally spaced above the carriage to provide a space 15 therebetween. The under surface of the carrier 7 is provided with a bearing surface for the spring 17, or other resilient means,

2

such as rubber, which bearing surface is called a spring boss 18.

The carriage 10 is provided with a stirrup 20 depending therefrom and through the tie bar 3. The lower part 21 of the stirrup 20 (see Figures 5 and 6) is provided with an inclined bearing surface 22 for the adjusting wedge 23 which supports a separate spring seat 24. The spring seat 24 is provided with lugs 25 which engage the slots 26 in the carriage 10 to hold them from lateral displacement, but permitting vertical movement of the seat 24. The coil spring 17, or other resilient means, is interposed between the spring boss 18 and the spring seat 24 to cushion the carrier 7 upon the stirrup of the carriage 10. The carriage is formed with an aperture 27 for the spring to pass therethrough. In this way a long, vertical spring may be used to obtain sufficient resilience and compression without abnormal compression of the spring which causes fatigue and failure.

The wedge 23 adjusts the height of the spring and carrier from the rail of the track (not shown) and the rivet 28 holds the wedge 23 in adjusted position.

25 In case of an abnormal vertical pressure upon the coupler 5 the spring 17 compresses and the carrier 7 rests upon the carriage 10. The same occurs in case of a spring failure.

In my arrangement the carrier 7 and the coupler 5 is resiliently supported continuously as the carrier and coupler move laterally.

The device is broadly applicable to coupler carriers wherein the carriage (or carrier) is swingably supported from a car part by spaced links, such as shown in Gilpin Patent No. 1,658,120 of February 7, 1928.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

45 1. A device for positioning and resiliently supporting a coupler upon a railway car having a member fixed to the car; said device comprising a carrier arranged to move laterally and vertically with a coupler and provided with a boss, a carriage movable laterally with the carrier and spaced below the carrier, said carrier provided with a spring seat, each end of said carriage and said member provided with a pair of mutually facing oppositely disposed concavely curved surfaces and each of said pairs having a roller there-

55

between and cooperative therewith to return the coupler to normal central position when free to do so, and a resilient element extending through said carriage and interposed between said boss and said seat to cushion the carrier against vertical shocks.

2. A structure as defined in claim 1 wherein the carrier is maintained above the carriage by said resilient element, except when the carrier engages the carriage upon a predetermined downward movement thereof and thus limits the compression of the resilient element.

3. A device for positioning and resiliently supporting a coupler upon a railway car having a member fixed to the car; said device comprising a carrier arranged to move laterally and vertically with a coupler and provided with a boss, a carriage movable laterally with the carrier and spaced below the carrier, said carrier provided with a spring seat, said carriage provided with means to return the coupler to normal central position when free to do so, and a resilient element extending through said carriage and interposed between said boss and said seat to cushion the carrier against vertical shocks.

4. A device for resiliently supporting a coupler upon a railway car having a member fixed to the car, said device comprising a carrier arranged to move laterally and vertically with the coupler, a carriage supported by said member,

and having spaced walls between which said carrier may reciprocate vertically, said carriage having a central transverse aperture therethrough, a vertically movable seat supported by said carriage, and resilient means extending through said aperture and interposed between said carrier and said seat to maintain said carrier spaced above said carriage except when said resilient means is excessively loaded.

5. A structure as defined in claim 4 including means to adjust the space between the carrier and said seat.

6. A structure as defined in claim 4 including means to adjust the space between the said seat and carriage, said means comprising an adjusting wedge interposed between said seat and a part of said carriage, and means to hold said wedge in place when adjusted.

KARL T. NYSTROM.
